UNITED STATES PATENT OFFICE.

ERNEST ELMER ENGLEMAN, OF ROANOKE, VIRGINIA.

WATER-PAN FOR HOT-AIR FURNACES.

1,362,932.

Specification of Letters Patent.

Patented Dec. 21, 1920.

Application filed March 5, 1920. Serial No. 363,388.

To all whom it may concern:

Be it known that I, ERNEST ELMER ENGLEMAN, a citizen of the United States, residing at Roanoke, in the county of Roanoke and

5 State of Virginia, have invented certain new and useful Improvements in Water-Pans for Hot-Air Furnaces, of which the following is a specification.

The present invention relates to means 10 for humidifying air passed through an air heating furnace.

The object is to provide a simple and effective structure which can be readily placed in position in a furnace without materially 15 altering the structure, and will not only supply vapor to the air passed through the furnace, but will also act as a collecting agent for dust and the like carried by the air or falling through the floor grating or other 20 openings.

A further object is to provide means whereby the water can be readily drawn off and as readily supplied.

An embodiment of the invention is illustrated in the accompanying drawings, wherein:—

Figure 1 is a view partly in elevation and partly in section of a well known type of furnace, showing the novel means in place 30 therein,

Fig. 2 is a horizontal sectional view,

Fig. 3 is a detail sectional view on an enlarged scale,

Fig. 4 is a horizontal sectional view of a 35 slightly modified form of construction.

Similar reference numerals designate corresponding parts in all the figures of the drawings.

In the embodiment disclosed, a so-called 40 "pipeless" furnace is employed containing a central combustion chamber 5 of any desired character surrounded by a casing 6 forming an air circulating chamber. This air circulating chamber is subdivided by a 45 cylindrical depending partition 7 into an outer annular air intake flue 8 and an inner outlet flue 9 that immediately surrounds the combustion chamber 5. A grating 10, as is well known, covers both the upper intake 50 end of the flue 8 and the discharge end of the flue 9. The partition 7 terminates short of the bottom of the furnace, affording communication between the lower ends of the flues 8 and 9.

55 In the space below the partition 7 and ex-

tending centrally from the wall of the combustion chamber 5 to the outer casing wall 6 is a circular water pan in the form of a V-shaped trough 11 having a central supporting flange 12 and having an inclined 60 bottom, as will be clear by reference to Fig. 3, the flange 12 tapering from one end to the other. A supply pipe 13 is connected to the higher end of the trough and extends outside the casing wall 6, being provided with 65 an upturned terminal 14, and in this upturned end can be placed a funnel 15 or other suitable fluid-directing means. From the lower end of the trough extends a discharge pipe 16, which may be closed by any 70 suitable means, as for example, a plug 17.

It will be obvious by reference to Fig. 1 that if water is placed in the pan or trough, the air passing through the furnace will pass over the surface of the water and therefore not only absorb water therefrom, but will give up a relatively great amount of dust and dirt carried by said air. This will gravitate into the pan and can be drawn off with the water by opening the discharge 80 pipe 16. A fresh supply can be introduced easily through the pipe 13.

As a modification of the structure above described, the means illustrated in Fig. 4 may be employed, the only difference being 85 that the trough is divided into sections 11^a, each of which is provided with a supply pipe 13^a and a discharge pipe 16^a.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

Having thus fully described my invention, what I claim as new and desire to secure by 100 Letters Patent, is:—

1. An air heating furnace comprising a combustion chamber, an air circulating chamber surrounding the same, and a water pan in the lower portion of the air circulating chamber and comprising an elongated trough having a bottom that inclines downwardly, means extending to the outside of the chamber for supplying liquid to the higher portion of the pan, and means con- 105 110

nected to the lower portion of the pan for drawing off the contents thereof to permit the flushing of said trough.

2. An air heating furnace comprising a combustion chamber, an air circulating chamber surrounding the same, a substantially V-shaped water trough in the lower portion of the air circulating chamber having a tapered supporting flange that provides a downwardly inclined bottom to the trough, means for supplying water to the

higher end of the trough, and means for drawing off the water from the lower end of the trough to permit the flushing of said trough.

15

In testimony whereof, I affix my signature in the presence of two witnesses.

ERNEST ELMER ENGLEMAN.
